PUSH BUTTON SWITCH OVERRIDE CLIP
Henry M. de Ronde, San Diego, Calif., assignor to The
Ryan Aeronautical Company, San Diego, Calif.
Filed Mar. 26, 1962, Ser. No. 182,278
5 Claims. (Cl. 200—169)

The present invention relates generally to push button type switches and more particularly to a push button switch override clip.

The primary object of this invention is to provide a clip for attachment to a push button switch to override and hold the push button in depressed position, and which will remain engaged even when subjected to extreme vibration and shock.

Another object of this invention is to provide a clip which is easily operable with one hand to lock or unlock the push button retaining means.

Another object of this invention is to provide a clip having only one moving part, which is positively retained against inadvertent removal or loss.

A further object of this invention is to provide a clip which is compact and is held in place by the means used to hold the push button switch, the clip being usable in virtually any position since clearance is necessary for operation of the push button.

Finally, it is an object to provide a push button switch override clip of the aforementioned character which is simple and convenient to manufacture and install and which will give generally efficient and durable service.

With these and other objects definitely in view, this invention consists in the novel construction, combination and arrangement of elements and portions, as will be herein-after fully described in the specification, particularly pointed out in the claims, and illustrated in the drawing which forms a material part of this disclosure, and in which:

FIGURE 1 is a perspective view of the complete clip;

FIGURE 2 is a top plan view of the clip attached to a push button switch;

FIGURE 3 is a sectional view taken on line 3—3 of FIGURE 2, but with the clip in locked position; and

FIGURE 4 is a sectional view taken on line 4—4 of FIGURE 2 and rotated 90 degrees.

The clip consists of only two parts, an elongated, U-shaped yoke 10 and a slide plate 12. The yoke 10 has a lower arm 14 and an upper arm 16 connected at one end by an arcuate bight portion 18, the element being made from flat sheet material and the arms being flat and convergent in relaxed condition, as in FIGURE 1. Since the bight portion 18 must be resilient, the yoke is preferably made from spring steel, or similar material, which will also ensure good wearing qualities. The longitudinal edges of the upper arm 16 have upwardly and inwardly turned flanged rails 20, the free end of said upper arm having an upwardly curved tongue 22 extending beyond the rails. The slide plate 12 is substantially the same width as the upper arm 16 and is a smooth sliding fit between rails 20, the ends of said slide plate having upwardly projecting lips 24. The rear ends of rails 20 adjacent bight portion 18 have downwardly turned stops 26 which prevent removal of slide plate 12, the upwardly curving tongue 22 at the forward end retaining the slide plate at that end.

The clip is illustrated in use with a push button switch 30 having a body 32 containing the switch mechanism and a threaded boss 34 through which extends the axially movable push button 36. The lower arm 14 of yoke 10 has a large opening 38 adjacent the free end thereof through which threaded boss 34 is fitted, the clip being held in place by a nut 40 normally used to secure the switch. When the switch 30 is secured to a panel or other structure, the panel would be disposed between the switch body 32

2

and lower arm 14, but has been omitted for simplicity since the actual mounting is widely variable. The upper arm 16 has a small opening 42, coaxial with opening 38, so that the push button can protrude above the upper arm, opening 42 being a loose clearance fit for said push button to avoid binding and allow for slight misalignment. Due to the normal convergence of arms 14 and 16, the upper arm 16 is held firmly down on the upper end of threaded boss 34, as in FIGURES 3 and 4, so that the greater portion of push button 36 is exposed and can be actuated in the normal manner.

To hold push button 36 down the upper arm 16 is raised clear of the push button by means of a finger, usually the index finger, under tongue 22, as indicated in broken line in FIGURE 3. Slide plate 12 can then be slid forwardly, by means of the thumb against either lip 24, to cover opening 42. When upper arm 16 is released, the push button 36 will then be depressed and held down by the slide plate 12, as indicated in full line in FIGURE 3. The push button is thus locked in the depressed position and held by the resiliency of the yoke 10, or primarily of bight portion 18. The underside of slide plate 12 is provided with a shallow socket 44 into which push button 36 seats to lock the slide plate against shifting and, by the upward pressure of push button 36, slide plate 12 is held tightly against the flanged rails 20. Since the inwardly turned flanges of rails 20 engage the entire longitudinal edges of slide plate 12, there is a considerable area of frictional contact. Further, the loads imposed in this locked position have no tendency whatsoever to shift the slide plate 12 from its position over the push button. Thus the assembly is extremely resistant to vibration and can withstand considerable shock in any direction without becoming disengaged. To enable the slide plate 12 to move, the upper arm 16 would have to be raised completely clear of push button 36, but if the resiliency of the yoke is sufficient to hold the push button down this is virtually impossible, even under conditions of continued vibration and shocks. The resistance to vibration and shock is of particular importance in the aerospace field, where vehicles utilizing such switch units may be subjected to extremes of environmental conditions and reliability is essential.

To release the push button, upper arm 16 is simply lifted by a finger under tongue 22 and slide plate 12 shifted by the thumb nail against a lip 24, so clearing opening 42. Stops 26 limit travel of the slide plate 12 and avoid the need for precise positioning to ensure clearance of opening 42, making the operation simple and rapid with one hand. With the clip in open or unlocked position no vibration or shock can make the slide plate 12 close over opening 42 inadvertently, due to the full extension of push button 36 above the upper arm 16 providing an obstruction.

While the clip is illustrated for attachment to a switch secured by a single nut, it will be obvious that the lower arm 14 could be provided with suitable holes for attachment screws of other types of switches. In any installation, however, the clip is as a unit with the switch, so that alignment and correct operation are ensured. Locking and unlocking are both accomplished by simple sliding actions of the only moving part, no tools of any kind being required. Both parts of the clip are easily fabricated from sheet material by simple stamping and bending operations in conventional machines.

It is understood that minor variation from the form of the invention disclosed herein may be made without departure from the spirit and scope of the invention, and that the specification and drawings are to be considered as merely illustrative rather than limiting.

I claim:

1. In combination with a switch having a body portion and an axially movable push button extending from said

body portion, a push button override clip, comprising:
 a resilient yoke having an upper arm and a lower arm;
 means to secure said lower arm to said body portion;
 said upper arm extending over said push button and
 having an opening through which the push button
 protrudes;
 a slide plate slidably mounted on said upper arm and
 being movable from a first position clear of said open-
 ing to a second position covering said opening,
 whereby said push button is held depressed into said
 body portion by said slide plate in said second po-
 sition.

2. In combination with a switch having a body portion and an axially movable push button extending from said body portion, a push button override clip, comprising:
 a resilient yoke having an upper arm and a lower arm;
 means to secure said lower arm to said body portion;
 said upper arm extending over said push button and hav-
 ing an opening through which the push button pro-
 trudes;
 the longitudinal edges of said upper arm having opposed
 flanged rails;
 a slide plate mounted on said upper arm and being slid-
 ably between said rails;
 said slide plate being movable from a first position clear
 of said opening to a second position covering the
 opening, whereby said push button is held depressed
 into said body portion by said slide plate in said sec-
 ond position.

3. In combination with a switch having a body portion and an axially movable push button extending from said body portion, a push button override clip, comprising:
 a resilient yoke having an upper arm and a lower arm;
 means to secure said lower arm to said body portion;
 said upper arm extending over said push button and
 having an opening through which the push button
 protrudes;
 the longitudinal edges of said upper arm having op-
 posed flanged rails;
 a slide plate mounted on said upper arm and being slid-
 ably between said rails;

 said rails having stops at one end to retain said slide
 plate;
 the end of said upper arm remote from said stops
 having an upwardly turned tongue portion;
 said slide plate being movable from a first position clear
 of said opening to a second position covering the
 opening, whereby said push button is held depressed
 into said body portion by said slide plate in said
 second position.

4. In combination with a switch having a body portion and an axially movable push button extending from said body portion, a push button override clip, comprising:
 a yoke having an upper arm, a lower arm and a resilient
 bight portion interconnecting said arms at one end;
 said lower arm having means for attachment to said
 switch body portion;
 said upper arm extending over said push button and
 having an opening through which the push button
 protrudes;
 the longitudinal edges of said upper arm having opposed
 flanged rails;
 a slide plate mounted on said upper arm and being slid-
 ably between said rails;
 said slide plate having an upwardly turned lip;
 said rails having slide plate retaining stops at the end
 adjacent said bight portion;
 the end of said upper arm remote from said bight por-
 tion having an upwardly turned tongue;
 said slide plate being movable from a first position clear
 of said opening to a second position covering the
 opening, whereby said push button is held depressed
 into said body portion by said slide plate in said
 second position.

5. The combination according to claim 4 and wherein
 35 said slide plate has a socket into which said push button
 seats when said slide plate is in said second position.
